CLAIM

I claim the ornamental design for an exercise device, as shown and described.

DESCRIPTION

FIG. 1 is a first perspective view of the exercise device from a generally front and upper perspective;

FIG. 2 is a second perspective view of the exercise device from a generally right-side perspective;

FIG. 3 is a third perspective view of the exercise device from a generally left-side perspective;

FIG. 4 is a fourth perspective view of the exercise device from a rear perspective; and,

FIG. 5 is a left side view of the exercise device, the right side view being a mirror image thereof.

The broken lines show stitching and environment and form no part of the claimed design.
